205,094

RETINOSCOPE

Arthur J. Pulos, Fayetteville, and Richard H. Chapman, Camillus, N.Y., assignors to Welch Allyn, Inc., Skaneateles Falls, N.Y., a corporation of New York

Filed May 17, 1965, Ser. No. 85,319

Term of patent 14 years

(Cl. D57—1)

FIG. 1 is a front elevation of a Retinoscope showing our new design,

FIG. 2 is a side elevation thereof,

FIG. 3 is a modified embodiment of the Retinoscope shown in FIG. 1, the difference residing in the sleeve-like member,

FIG. 4 is a side elevation of the form shown in FIG. 3.

The proximal head portion of the Retinoscope shown in FIGS. 1 and 2 is the same as said portion shown in FIG. 3.

The broken lines are shown for illustrative purposes only.

We claim:

The ornamental design for a retinoscope, as shown and described.

References Cited by the Examiner

UNITED STATES PATENTS

D. 119,555	3/1940	Miles	-----	D83—12
D. 175,322	8/1955	Stegeman	-----	D57—1
D. 202,659	10/1965	Herold	-----	D57—1
3,035,483	5/1962	Andreas et al.

OTHER REFERENCES

Journal of Amer. Medical Assoc., Feb. 20, 1960, page 254, Welch Allyn Rechargeable Handle.

WALLACE R. BURKE, Primary Examiner.

BERNARD ANSHER, Assistant Examiner.